UNITED STATES PATENT OFFICE.

WILLIAM OREM, OF BALTIMORE, MARYLAND, ASSIGNOR TO R. A. CARMICHAEL & CO., OF DETROIT, MICHIGAN.

DESIGN FOR A PERFUME-BOTTLE.

47,434.

Specification for Design.

Patented June 8, 1915.

Application filed January 18, 1915. Serial No. 2,987. Term of patent 14 years.

To all whom it may concern:

Be it known that I, WILLIAM OREM, a citizen of the United States, residing in the city of Baltimore and State of Maryland, have invented a new, original, and ornamental Design for Perfume-Bottles, of which the following is a specification, reference being had to the accompanying drawing, forming part thereof.

Figure 1 is a front elevation of a perfume bottle, showing my new design. Fig. 2 is a side elevation. Fig. 3 is a top plan view.

I claim:

The ornamental design for a perfume bottle, as shown.

WILLIAM OREM.
